UNITED STATES PATENT OFFICE.

HENRY H. CUTLER, OF BROOKLINE, MASSACHUSETTS.

INTERNAL-COMBUSTION ENGINE.

Application filed March 22, 1924. Serial No. 701,051.

My invention relates to internal combustion engines and more especially to such engines of the variable clearance type in which means are provided for varying the clearance space in unison with the movement of the power piston whereby the volume of such clearance space is made to vary in such close relation to the load upon the engine that the degree of compression 5 may be maintained practically constant at all loads.

A further object of my invention is to utilize the same mechanism for mechanically scavenging the cylinder after every 15 explosion, and a still further object of my invention is to provide a very large amount of resilient recoil at the time of each explosion of the working mixture in the engine cylinder whereby the strain upon the 20 crank shaft and the reciprocating parts is reduced to from one-half to one-third of normal, thus making it practicable to employ a compression pressure twice as high as possible in the usual form of combustion 25 engines without producing knocking.

The present invention is a development of that disclosed in my application Serial No. 445,690, filed February 17, 1921, of which this application is a continuation.

The principal feature of my invention is the provision of an air reservoir from which the air cannot escape during the operation of the engine, so that the pressure of this 30 confined air may be kept approximately constant, and utilized to control the resulting and corresponding compression in the engine cylinders. This feature I obtain by novel means as well as the use of modern and recently developed methods of manufacturing.

In the accompanying drawings which show embodiments of my invention—

Figure 1 is a central vertical section of one of the cylinders of an internal combustion engine, embodying my invention, and showing the relative position of the moving parts on completion of the scavenging or exhaust stroke of the power piston of the engine;

Fig. 2 is a similar section showing the relative position of the same moving parts on completion of the compression stroke;

Fig. 3 is another similar section showing the position of the same moving parts at the beginning of the power stroke, or just after the working mixture has been fired;

Fig. 4 is a top plan view of a four-cylinder engine embodying my invention, and showing certain electrical and pneumatic connections and appliances;

Fig. 5 is a development of the commutator;

Fig. 6 is a horizontal section taken on line C—D of Fig. 2 and showing a top view of the electro-magnet;

Fig. 7 is a top plan view (partly in section) through line A—B of Fig. 1 of a four cylinder engine embodying my invention, and showing a method of controlling the electro-magnets differing from that shown in Figs. 4 and 5;

Fig. 8 is an elevation, partly in section, on an enlarged scale, of the pressure-actuated electric circuit breaker illustrated in Fig. 7.

In the drawings which are to be taken as illustrative merely, and not as restrictive, I show in place of the usual demountable head, a single unit head consisting of the casting 17, secured by bolts 17' (Fig. 4), to the top of the cylinder block 14 in the usual manner. In the casting 17, cylinders 18, 19, 20 and 21 are formed and constitute extensions (of preferably smaller diameter) of the corresponding cylinders of the main engine block 14. At the extreme end of each of these cylinder extensions is a fixed head or plug 22, each head being hollow and connected with the water jacket by passageways 26, 26. It is essential that these fixed heads 22 shall make a gas and water-tight joint with the walls of the cylinder in which they are placed. This result I obtain by accurately grinding the heads 22 a few thousandths of an inch larger in diameter than the bore of the cylinders, then heating the entire cylinder casting 17 and placing the heads therein cold, so that when the cylinder head casting 17 cools, the heads 22 are firmly gripped. This process has been found in practice to be sufficient not only to make a perfect water and gas-tight joint, but also to stand the pressure of the exploded gases under working conditions.

Arranged for longitudinal movement in each cylinder is a member 28, the portion or volume of each cylinder between each power piston 32 and said movable member 28 forming a compression chamber 75, and means are provided for automatically controlling the position of said movable member 28 so as to vary the volume of said compression

chamber 75 in practically exact accordance with the variation of the load on the engine, thus keeping the degree of compression approximately the same at all times. The position of said movable member 28 is controlled automatically and resiliently for the purpose above specified and after each explosion of the working mixture, the position of said movable member 28 is automatically changed 10 so as to greatly enlarge the volume of compression chamber 75 and thereby greatly reduce the resulting pressure of the exploded gases upon the reciprocating parts of the engine. At the completion of the power stroke the movable member 28 has been automatically moved towards the power piston 28, and smoothly brought to a stop in such a position as to effect almost complete mechanical scavenging of the engine cylinder on the completion of the exhaust stroke of the power piston 32, as shown in Fig. 1.

In Figs. 1, 2 and 3 is shown a pressure or dash-pot piston 39 arranged to work in a cylinder 37 formed by an extension of the fixed head 22. This extension 37 is preferably a brass casting bored out to precisely the same diameter as the cylinder 18 in the casting 17 and then heated and shrunk onto the plug 22 just as the casting 17 was also shrunk on. On top of each cylinder 37 is a rectangular flange shaped off so that when mounted on one of the plugs 22 this rectangular flange will abut upon the flange of the adjacent casting 37. These flanges are bevelled on all four sides which results in the formation of a V-shaped cavity where the flanges abut against each other. These cavities are then filled in with metal melted by the process of electric arc welding, and then the entire surface is planed off smooth.

Each pressure piston 39 is connected with its respective scavenging piston 28 by means of a long rod 40. Said rod is preferably made of low carbon steel, pack hardened, and accurately ground so as to make a free but close fit in a carefully reamed hole in the fixed head 22. The lower end of said rod 40 has a head 41 and is held to the scavenging piston 28 by means of a washer 42 riveted to the bottom of the piston 28 with rivets 43. The head 41 is preferably slightly smaller in diameter than the hole in the piston 28 and the hole in the washer 42 slightly larger than the diameter of the rod 40 so as to allow of a very slight side play of the rod 40 leaving it free to center itself in the hole in the plug 22, without tendency to bind. Likewise an easy fit is made where the rod passes through the pressure piston 39. A nut 44 is then screwed on to the threaded end of the piston rod 40, thus connecting rigidly together the scavenging piston 28 and its pressure piston 39. A taper pin 44^a (Fig. 1) is then driven through the nut 44 and its small

end headed over. In the bottom of the rod 40 is shown a cylinder 45 (Fig. 3) arranged to slide freely in a hole in the rod 40 and pressed up by a spring 46. The end of the cylinder 45 terminates in a rod 47 to which is riveted a conical valve 48 after the rod 40 has been attached to the piston 28. Said valve 48 seats in the bottom of the piston 28 so as to form a valve free to open into the engine cylinder whenever the pressure in the compression chamber 76 exceeds the pressure in the chamber 75. The pressure piston 39 also contains a small valve 50 held down by a spring 51 and seating on the inside of said piston 39, and free to open whenever the pressure in the chamber 77 (formed between the bottom of the pressure piston 39 and the top of the head 22), exceeds to a predetermined degree the pressure in the air reservoir or chamber 78 above the pressure piston 39.

Inserted in a circular chamber turned out in the top of the plug head 22 is a coil of insulated wire 53. The inside terminal of the wire coil 53 is soldered to a thin brass tube made to fit closely over the central pole 54 of the circular magnet formed in the end of the plug head 22. The outside terminal of the coil 53 passes through a hole in the plug head 22 and then through a threaded hole 55 drilled through the cylinder 37 opposite the hole in the head 22. A threaded bushing 56, preferably of tough insulating material, is screwed up solid against some asbestos thread packing, thereby forming an air-tight packing around the terminal wire of the coil 53. A locknut 57 is also shown in Fig. 1. A brass disc 58 turned slightly larger in diameter than the inside of the chamber which holds the coil 53 and having a hole in the center somewhat smaller in diameter than that of the central magnet pole 54 is then pressed down against a shoulder cut in the poles of the electric magnet so as to make an air-tight fit. The depth of this shoulder is such that the top surface of the brass plate 58 when in position will be about one-hundredth of an inch lower than the surface of the magnet poles so that when the pressure piston 39 makes mechanical contact with the poles of the electro-magnet 53, a minute air chamber 77 is formed between them. A number of slots 60 (Fig. 6) have previously been ground one-hundredth of an inch deep in the outside pole of the magnet 53.

After all the above mentioned parts have been assembled as described, the open tops of the various cylinders 37 are covered by a plate casting 61. A depression 62 is cast in the said plate so as to form a passageway connecting together all four of the cylinders shown in Fig. 4. The outside edges of the plate 61 are bevelled so that a V-shaped groove is formed all around the edges, be-

tween the cylinders 37 and the plate 61. This V-shaped cavity thus formed is then filled with metal melted by the process of electric arc welding, resulting in an absolutely perfect air-tight joint between the plate 61 and the cylinders 37 which it covers. For convenience in removing some of the reciprocating parts, closed threaded nipples 63 are shown screwed into the top of the plate 10 61.

The pressure pistons 39 and the wire coils 53 cannot be removed without first chipping or grinding out the metal melted into the V-shaped groove in the plate 61.

15 The magnet coils 53 are shown in Fig. 4 as being energized and de-energized by means of a small commutator 64 mounted at the end of the casting 17 and driven by a small sprocket wheel 65, connected by a 20 chain with another sprocket wheel 65^a mounted on the projecting end of the engine crank shaft, said sprocket wheel 65^a having one-half the number of teeth as the wheel 65. The commutator 64 contains five sets of 25 rings 66 embedded in insulating material. The rings 66 make contact with five brushes 67. Four of these brushes 67 connect with the outside terminals of the four magnet coils 53 respectively. The fifth brush 67^e 30 connects with the negative terminal of the storage battery 68 after first passing through a small rheostat 69 which controls the amount of current supplied by the storage battery 68 to all of the magnet coils 53. The 35 rheostat 69 is supplied with four extra contact buttons 70 which connect directly as shown, with the four coils 53, respectively.

The rheostat is also provided with a segment 71, which segment is connected with 40 the primary coil or coils of the ignition system of the engine.

Two phosphor bronze brushes (not shown) are screwed to the bottom of the rheostat lever 72 in the usual manner in rheostat 45 practice, so as to make contact with the resistance buttons 73 and the segment 71, respectively. The hub of the rheostat lever 72 is connected with the negative terminal 50 of the storage battery 68. The rheostat lever 72 is shown in Fig. 4 in the off-position, in which position the circuit is open both to the ignition coil or coils and all the magnet coils 53. Moving the lever 72 to the right closes the ignition circuit and also 55 such of the magnet coils 53 as are connected by means of the brushes 67 and commutator segments 66. Moving the rheostat lever 72 to the left first opens the ignition circuit and then connects all the magnet coils 53 directly 60 across the battery 68 without first including any of the resistance of the rheostat 69. A small flat steel spring 121 shown in Fig. 7 returns the lever 72 to the off position, if the lever is moved to the left and then 65 released.

Fig. 5 shows the development in one plane of the outside circumference of the commutator 64. All of the white segments are electrically dead, so that whenever one of the brushes 67 makes contact with a white segment, the circuit is broken. The black segments are all electrically connected with the complete ring segment 67 which connects with the negative of the storage battery 68 through the resistance of the rheostat 69. 70 Spark plugs 74 are shown in Figs. 1, 2, 3 and 4.

The air reservoir 78 (Fig. 4) is connected by piping 80 with a Bourdon pressure gauge 81, and also to a taper gas cock 82. A small 80 hand-operated air pump 83 is connected to the gas cock 82. The said cock 82 has two holes drilled from the outside at right angles to each other and meeting in the center as shown in Fig. 7 so that by turning the cock 85 82 in one direction the reservoir 78 may be connected with the outside air, and by turning the cock in the other direction the air reservoir 78 may be connected with the air pump 83. All threaded pipe connections, 90 etc., are preferably electric welded.

Before assembling the above mentioned parts of my invention, each pressure piston 39 is temporarily fastened to its piston rod 40 which is then inserted in the hole reamed out in the plug head 22. The piston 39 is then ground against the poles of the magnet 53 so as to make an air-tight valve between the bottom of the piston 39 and the central pole 54 of the electro-magnet 100 53. The high spots on the outside pole of the electro-magnet are scraped by hand so that the piston 39 will touch only the central pole 54, the surface of which may also be hand scraped together with the contacting surface of the piston 39. 105

Having assembled all the above described parts and made all of the electrical and pneumatic connections shown and described, the rheostat lever 72 is moved to the left so 110 as to fully energize all four of the magnet coils 53 and cause all four of the pressure pistons 39 to be held firmly against the central poles 54 of the electro-magnets. The rheostat lever 72 may then be released and 115 thus allowed to return to its open circuit or off position. The electro-magnets 53 having thus been fully magnetized will retain sufficient residual magnetism to hold the pressure pistons 39 to their seats, and 120 thus preserve an air-tight joint between the air reservoir 78 and the only possible avenue of escape for any air in the reservoir 78 by leaking by the outside of the long piston rods 40. 125

The taper cock 82 may be turned so as to connect the air pump 83 with the air reservoir 78 and filtered air free from dust pump into the reservoir until it has reached a pressure as shown by the gauge 81, of say, 130

150 pounds. The taper cock 82 may then be closed, leaving the air, so far as all practical conditions are concerned, permanently confined in the air reservoir 78. In the course of time this air will eventually find a place to leak out just as it does eventually in an automobile tire. During the operation of the engine however, as will be pointed out later, there is practically no opportunity for the escape of this confined air.

The total volume of the air reservoir suitable for a 4" x 3 $\frac{1}{4}$ " four cylinder engine figures about one-eighth the volume of a thirty by three and one half inch automobile tire.

The perfection of the air-tight reservoir is obtained by first abandoning any attempt to confine this air back of a piston equipped with piston rings as with such construction it has been found impossible to confine the air, second, by eliminating all gaskets, and stuffing boxes subject to mechanical wear, and third, by electric welding each and every joint.

Figs. 7 and 8 show a different method of controlling the circuit of the electro-magnet 53. Fig. 8 is a full size detailed drawing showing a small cylinder 101 containing a small piston 102 normally held down on its seat by a spring 103. The threaded end of the cylinder 101 is preferably screwed into the casting 17 over the valve chamber in a similar manner as the spark plugs 74, so that the piston 102 is at all times exposed to the pressure in the engine cylinder and free to move up as soon as the pressure in the engine cylinder becomes strong enough to overcome the pressure of the little spring 103. The end of the piston 102 terminates in a rod 104 arranged to slide freely through a hole in the threaded cap 105 which closes the cylinder 101. The threaded end of the rod 104 is screwed into a button 106 of insulating material. This button when moved upwards by the piston 102 and its rod 103, presses against a flat steel spring 107 which is fastened to a binding-post or block 108. The other end of the flat spring 107 is riveted to a piece of coin silver 109. The silver point 109 makes mechanical and electrical contact with another piece of coin silver 110 so as to make a scraping contact as distinguished from a button contact, which first method has been found by long experience to be much more reliable. The silver contact piece 110 is fastened to another binding block 111. The entire electrical mechanism just mentioned is mounted on a block of insulating material 112 which is screwed to the casting 17 as shown in Figs. 1 and 7. Mounted also on the block 112 is a small lamp receptacle 113 holding a small incandescent lamp 114 designed normally to burn at a pressure of from 12 to 15 volts. One terminal of the lamp 114 is connected to

the binding block by means of the wire 115, and the other terminal of the lamp connects by means of wire 116 to the casting 17. Each binding block 111 is connected with the outside terminal of its respective magnet coil 53, there being one of the above described pressure-actuated electric circuit breakers for each cylinder of the engine. All the binding blocks 108 are connected electrically by the wire 117 which terminates in the end terminal button 118 of the rheostat 69. The hub of the rheostat lever 72 is connected by means of the wire 119 with the negative terminal of the storage battery 68. The rheostat lever 72 is shown in its open circuit or off position. Moving the lever 72 to the right closes the circuit to all the magnet windings 53, including any desired portion of the rheostat resistance in circuit. Moving the rheostat lever to the left makes it contact with the short circuiting button 70 which is connected by a wire 120 with the terminal button 118 of the rheostat 69. A flat spring 121 pushes back the rheostat lever 72 to the off position if moved to the left and then released.

All the electric switches above described are normally closed so as to keep the magnet coils 53 energized. These switches are opened however with a quick snappy motion as soon as the compression stroke of the engine increases the pressure sufficiently to lift the little piston 102. This opens the circuit to the respective magnet coil 53 and the extra current induced in the magnet coils on the opening of the circuit discharges through the non-inductive resistance of the filament of the little lamp 114, thereby preventing any destructive arcing between the silver points 109 and 110.

On the opening of the exhaust valve of the engine, the pressure drops in the engine cylinder, the little piston 102 returns to the position shown in Fig. 8, the switch 107 closes, and the magnet coil 53 becomes energized again.

The operation is as follows:—

On account of the very large amount of resilient recoil which occurs at the moment the working mixture is fired, an engine embodying my invention may be operated without knocking at very much higher compression pressures than is allowable in the engines in common use. With a compression pressure of 150 pounds gauge and a mixture unadulterated with a large percentage of exhaust-gases, the firing of such a mixture results in an extremely violent explosion which breaks the spark plugs and tends to smash up things generally, unless a liberal amount of resilient recoil is provided. It is like firing a coast defense gun bolted to a solid foundation and unprovided with a large resilient recoil.

With air in the reservoir 78 compressed

to 150 or even 100 pounds, it is evident that the power piston 32 will have to approach very close to the scavenging piston 28 on its inward compression stroke before sufficient compression pressure will develop to force the pressure piston 39 more than a few hundredths of an inch from its seat. The scavenging piston 28 will then (theoretically) assume a position similar to that shown in Fig. 2, but practically the explosion will follow so closely afterwards that the piston 28 will have no time to linger in such a position, but will continue its motion and immediately assume a position similar to that illustrated in Fig. 3.

It is evident that the pressure piston 39 will be shot up into the air chamber 78 by the violence of the exploded gases until a position is reached such that the greatly reduced pressure in the explosion chamber 75 becomes somewhat less than the pressure of the air in the reservoir 78 plus the pressure of the air compressed in the chamber 76.

If the chamber 76 was of infinite size, then the resulting pressure of the explosion would at once fall to that of the pressure in the air reservoir 78. With a moderate size chamber 76 it becomes practical to reduce the pressure of the explosion to from one-third to one-half of normal, depending upon the pressure carried in the air reservoir and the load upon the engine.

At the instant immediately following the explosion the pressure of the air underneath the pressure piston 39 in the chamber 77 is very much less than that of the outside atmosphere, while the pressure of the air in the chamber 76 is very much greater than atmospheric pressure. An invitation is therefore extended for air to leak by the piston rod 40 from the chamber 76 into chamber 77 and thereby tend to increase the amount of air in the reservoir 78; later on, at the end of the power stroke, there exists a theoretical invitation for air to leak back the other way from the air chamber 77 to the chamber 76.

Theoretically speaking, the first tendency seems to be the stronger practically speaking if any leakage by the piston rod does occur it is extremely small and does not interfere with the operation of the engine.

In case an air leak should develop, extra air may be supplied as shown in Fig. 3. A small hole 90 may be drilled through the end of the piston rod 40 and then plugged up by the screw 91. Near the middle of the hole 90 is a pin hole 92 drilled through the rod 40 to meet the hole 90. The diameter of the rod 40 is also somewhat reduced by a groove 93 surrounding the pin hole 92. Further up on the rod 40 is another pin hole 94 drilled to meet the hole 90. For a short period immediately following the explosion the hole 94 enters into the chamber

77, thereby allowing a minute amount of air to be drawn into the chamber 77 from the outside atmosphere by way of the hole 95 drilled through the head 22. This construction causes the pressure of the air in the reservoir 78 to very slowly increase as will now be explained.

As the power piston 32 descends into the engine cylinder on its power stroke, the burning gases expand and their pressure diminishes so that at some time before the exhaust valve opens, the pressure of the air in the reservoir 78, plus the pressure of the compressed air in the chamber 76, will have forced down the scavenging piston 28 together with the pressure piston 39 until the latter touches or almost touches the poles of the electro-magnet 53. While the power stroke has been taking place, air from the reservoir 78 has been leaking in a steadily decreasing amount around and by the pressure piston 39 into the chamber 77 underneath the piston 39 so that when the piston 39 approaches closely to its seat on the poles of the electro-magnet 53, a film of air is interposed between them contained in the now extremely small chamber 77. After the engine has made a number of revolutions, the air which leaks by the piston 39, rapidly accumulates, and being compressed in the chamber 77, the piston 39 cannot seat itself upon the poles of the electro-magnet 53. If this action were

allowed to go on indefinitely, the pressure piston 39 would be stopped farther and farther away from its seat and would finally cease to function. The function of the electromagnets now becomes apparent. Approximating the time of opening of the exhaust valve the electro-magnet 53 becomes energized by means of the revolving commutator 64 (Fig. 4) or the switch 109 (Fig. 7); the magnet 53 then pulls the piston 39 down against its poles, thereby still further compressing the air in the minute air chamber 77, now reduced to a height of one-hundredth of an inch, as previously described.

The process of accumulating air in the chamber 77 continues as the engine operates, until finally the pressure of the air confined in the minute chamber 77 becomes great enough to lift the relief valve 50 and thereby return the excess air to the reservoir 78. The electro-magnet 53 acts therefore as an air pump returning the air to the reservoir 78 as fast as it manages to leak by the piston 39. The electro-magnet 53 is then kept magnetized until sometime during the compression stroke (it being immaterial just when), when its brush runs on to a dead segment of the commutator 64 (Fig. 4), or by the increase in pressure during the compression stroke lifting the little piston 102 (Fig. 7) whichever system is used.

The strength of the spring 51 and the

taper of the valve 50 are designed so as to allow plenty of air to be trapped between the pistons 39 and the brass plate 58 sufficiently to effect a smooth and noiseless stop of the reciprocating pistons 28 and 39. The electro-magnet 53 then becomes energized and pulls the piston 39 the few hundredths of an inch necessary to bring the piston 39 against the poles of the magnet 53 and force out the 10 surplus leakage of air back through the relief valve 50. While the electro-magnets 53 are shown quite powerful relative to the work they are called upon to perform, this work requires so little power that the current used for energizing the electro-magnets 53 may be greatly reduced by means of the rheostat 69.

It is an accepted fact that all pistons provided with piston rings as used in internal 20 combustion engine leak. Consequently, the scavenging pistons 28 will also leak so that during the compression stroke a small amount of the working mixture will leak by the rings of the piston 28, as well as a 25 certain amount of lubricating oil. This working mixture however is not lost, but is returned to the engine cylinder by way of the valve 48, together with any accumulation of lubricating oil during the following intake stroke of the engine.

By means of the taper cock 82 and the hand air pump 83, or the compression tank 100 filled with filtered air under high compression, the operator may run the engine 30 at any degree of compression desired. The engine will operate under low compression without any pressure in the air reservoir 78, or the compression can be gradually increased until the working mixture becomes 35 self-igniting. To operate the engine continuously at some predetermined degree of compression, a relief valve (not shown) may be connected with the air reservoir 78 and excess air allowed to be supplied by means 40 of the holes 90, 91, 92, 93, 94 and 95, Fig. 3, through the pipe 96, connected with an air filter (not shown). It is furthermore possible to operate the engine with the magnet coils 53 permanently energized, since 45 at the beginning of the compression stroke the piston 39 is subjected to substantially the same air pressure on both sides so that a comparatively small amount of compression will overcome the strength of the magnet 53 and lift the piston 39 a short distance from the magnet 53, in which position the air pressure above the piston 39 becomes effective. This method of operation dispenses 50 with all apparatus shown for energizing and de-energizing the magnet coils 53. On stopping the engine for any length of time the rheostat lever 72 is turned to the left as far as it will go and then released. This 55 fully saturates all the electro-magnets 53 which attract the pistons 39 firmly against

the poles of the magnets 53, which magnets retain sufficient residual magnetism to continue to attract the pistons 39, and hold them to their seats after the current is shut off. By these means the air compressed in the 70 reservoir 78 is prevented from eventually leaking out by way of the piston rods 40. The air compressed in the then minute air chamber 77 then gradually works its way through the channels 60 back around the 75 pressure piston 39 until the pressure of the air becomes the same on both sides of the piston 39.

I believe it to be broadly new with me to use an air-tight chamber for controlling the 80 position of a movable member located between the power piston and the closed end of the cylinder whereby to vary the volume of the compression chamber in accordance with the variation of the load on the engine. 85

Having thus described illustrative embodiments of my invention without however limiting the same thereto, what I claim and desire to secure by Letters Patent is:

1. An internal combustion engine comprising in combination a cylinder, a power piston therein, a hermetically-sealed chamber secured to and forming an extension of said cylinder, a fixed head intermediate the ends of said cylinder, a movable member on one side of said head forming a compression chamber of variable volume between said power piston and said movable member, a second movable member on the other side of said fixed head, and means passing through said head and rigidly connecting said movable members, the said movable members being constructed and arranged to pump gas during the operation of the engine into said hermetically-sealed chamber and confine the same without any appreciable loss either into the outside atmosphere, or into said compression chamber of the engine. 100

2. An internal combustion engine comprising in combination a cylinder, a power piston therein, a hermetically sealed chamber enclosing a gas under pressure, and movable means for varying the volume of the compression chamber of the engine in accordance with the pressure of the gas in 110 said hermetically-sealed chamber, said movable means being constructed and arranged to pump gas into said hermetically-sealed chamber and confine the same without any appreciable loss either into the outside atmosphere or into the compression chamber 115 of the engine. 120

3. An internal combustion engine comprising in combination, a cylinder, a hermetically sealed chamber enclosing a gas under pressure, and movable means for automatically varying the volume of the compression chamber in accordance with the variation of the load on the engine, the said movable means being constructed and ar- 125 130

- ranged to pump gas into said hermetically-sealed chamber and confine the same without appreciable loss either into the outside atmosphere or into said compression chamber.
5. An internal combustion engine comprising in combination, a cylinder, a power piston therein, a movable member in said cylinder, the portion of the cylinder between said piston and said member forming a compression chamber, and means for automatically controlling the position of said member to vary the volume of said compression chamber in accordance with the variation 10 of the load on the engine and for automatically changing the position of said member to scavenge the cylinder after every explosion.
15. An internal combustion engine comprising, in combination, a cylinder, a power piston therein, a movable member in said cylinder, the portion of the cylinder between said piston and said member forming a compression chamber, and resilient means 20 for automatically controlling the position of said member to vary the volume of said compression chamber in accordance with the variation of the load on the engine and for automatically changing the position of said member to scavenge the cylinder after every explosion.
25. An internal combustion engine comprising in combination, a cylinder, a power piston therein, a movable member in said cylinder, a hermetically sealed chamber forming an extension of said cylinder and enclosing a gas under pressure, a valve for preventing the escape of said gas into said cylinder at any point in the cycle of the 30 engine, and means whereby the pressure of said gas will cause said member automatically to vary the volume of the compression chamber in accordance with the variation of the load on the engine, said means being constructed and arranged to pump gas into said hermetically-sealed chamber and confine the same without any appreciable loss either into the outside atmosphere, or to said compression chamber.
35. An internal combustion engine comprising in combination, a cylinder, a fixed head intermediate the ends of said cylinder, a power piston in said cylinder on one side of said head, a scavenging piston located between said head and said power piston, said scavenging piston being constructed and arranged to form with said head an airtight chamber, a dash-pot piston on the other side of said head and means passing through said head and rigidly connecting said scavenging piston and said dash-pot piston.
40. An internal combustion engine comprising in combination, a cylinder, a fixed head intermediate the ends of said cylinder, a power piston in said cylinder on one side of said head, a scavenging piston located between said head and said power piston, a dash-pot piston on the other side of said head, means passing through said head and rigidly connecting said scavenging piston and said dash-pot piston, a hermetically sealed cylindrical chamber secured to and forming an extension of said cylinder, said dash-pot piston being reciprocable in and closely fitting said chamber, whereby the inward face of said dash-pot piston is subjected to the pressure of the gas confined in said chamber to limit the inward movement of said scavenging piston during each power stroke.
45. An internal combustion engine comprising in combination, a cylinder, a fixed head intermediate the ends of said cylinder, a power piston in said cylinder on one side of said head, a scavenging piston located between said head and said power piston, a dash-pot piston on the other side of said head, means passing through said head and rigidly connecting said scavenging piston and said dash-pot piston, a hermetically sealed cylindrical chamber secured to and forming an extension of said cylinder, said dash-pot piston being reciprocable in and closely fitting said chamber, whereby the inward face of said dash-pot piston is subjected to the pressure of the gas confined in said chamber to limit the inward movement of said scavenging piston during each power stroke, and a valve located in said dash-pot piston and arranged for actuation by the pressure in the chamber between the outward face of said dash-pot piston and said fixed head, thereby to open a passageway through said dash-pot piston.
50. An internal combustion engine comprising in combination, a cylinder, a fixed head intermediate the ends of said cylinder, a power piston in said cylinder on one side of said head, a scavenging piston located between said head and said power piston, said scavenging piston being constructed and arranged to form with said head an airtight chamber, a dash-pot piston on the other side of said head and means passing through said head and rigidly connecting said scavenging piston and said dash-pot piston.
55. An internal combustion engine comprising in combination, a cylinder, a fixed head intermediate the ends of said cylinder, a power piston in said cylinder on one side of said head, a scavenging piston located between said head and said power piston, a dash-pot piston on the other side of said head, means passing through said head and rigidly connecting said scavenging piston and said dash-pot piston.
60. An internal combustion engine comprising in combination, a cylinder, a fixed hollow head intermediate the ends of said
7. An internal combustion engine comprising in combination, a cylinder, a power piston in said cylinder on one side of said head, a scavenging piston located between said head and said power piston, a dash-pot piston on the other side of said head, means passing through said head and rigidly connecting said scavenging piston and said dash-pot piston.
8. An internal combustion engine comprising in combination, a cylinder, a fixed head intermediate the ends of said cylinder, a power piston in said cylinder on one side of said head, a scavenging piston located between said head and said power piston, a dash-pot piston on the other side of said head, means passing through said head and rigidly connecting said scavenging piston and said dash-pot piston.
9. An internal combustion engine comprising in combination, a cylinder, a fixed head intermediate the ends of said cylinder, a power piston in said cylinder on one side of said head, a scavenging piston located between said head and said power piston, said scavenging piston being constructed and arranged to form with said head an airtight chamber, a dash-pot piston on the other side of said head, means passing through said head and rigidly connecting said scavenging piston and said dash-pot piston.
10. An internal combustion engine comprising in combination, a cylinder, a fixed head intermediate the ends of said cylinder, a power piston in said cylinder on one side of said head, a scavenging piston located between said head and said power piston, a dash-pot piston on the other side of said head, means passing through said head and rigidly connecting said scavenging piston and said dash-pot piston, a hermetically sealed cylindrical chamber secured to and forming an extension of said cylinder, said dash-pot piston being reciprocable in and closely fitting said chamber, whereby the inward face of said dash-pot piston is subjected to the pressure of the gas confined in said chamber to limit the inward movement of said scavenging piston during each power stroke.
11. An internal combustion engine comprising in combination, a cylinder, a fixed head intermediate the ends of said cylinder, a power piston in said cylinder on one side of said head, a scavenging piston located between said head and said power piston, a dash-pot piston on the other side of said head, means passing through said head and rigidly connecting said scavenging piston and said dash-pot piston.

- rigidly connecting said scavenging piston and said dash-pot piston, a hermetically sealed cylindrical chamber secured to and forming an extension of said cylinder, said dash-pot piston being reciprocable in and closely fitting said chamber, whereby the inward face of said dash-pot piston is subjected to the pressure of the gas confined in said chamber to limit the inward movement of said scavenging piston during each power stroke, and means whereby the gaseous leakage around said dash-pot piston is forced back into the inward portion of said chamber without loss of pressure.
13. An internal combustion engine comprising, in combination, a cylinder, a fixed head intermediate the ends of said cylinder, a power piston in said cylinder on one side of said head, a scavenging piston located between said head and said power piston, a dash-pot piston on the other side of said head, means passing through said head and rigidly connecting said scavenging piston and said dash-pot piston, a hermetically sealed cylindrical chamber secured to and forming an extension of said cylinder, said dash-pot piston being reciprocable in and closely fitting said chamber, whereby the inward face of said dash-pot piston is subjected to the pressure of the gas confined in said chamber to limit the inward movement of said scavenging piston during each power stroke, and a magnetically-actuated pump for forcing back into the inward portion of said chamber the gaseous leakage around said dash-pot piston.
14. An internal combustion engine comprising, in combination, a cylinder, a fixed head intermediate the ends of said cylinder, a power piston in said cylinder on one side of said head, a scavenging piston located between said head and said power piston, a dash-pot piston on the other side of said head, means passing through said head and rigidly connecting said scavenging piston and said dash-pot piston, a hermetically sealed cylindrical chamber secured to and forming an extension of said cylinder, said dash-pot piston being reciprocable in and closely fitting said chamber, whereby the inward face of said dash-pot piston is subjected to the pressure of the gas confined in said chamber to limit the inward movement of said scavenging piston during each power stroke, a magnetically-actuated pump for forcing back into the inward portion of said chamber the gaseous leakage around said dash-pot piston, and means controlling said pump synchronously with said power piston.
15. An internal combustion engine comprising, in combination, a cylinder, a hermetically sealed cylindrical chamber secured to and forming an extension of said cylinder, a piston reciprocable in and closely fitting said chamber, a fluid pressure reservoir, a conduit connecting said reservoir with said chamber, and means for forcing back into the inward portion of said chamber gaseous leakage around said piston into the outward portion of said chamber without loss of pressure.
16. An internal combustion engine comprising, in combination, a cylinder, a fixed head intermediate the ends of said cylinder, a power piston in said cylinder on one side of said head, a scavenging piston located between said head and said power piston, a dash-pot piston on the other side of said head, means passing through said head and rigidly connecting said scavenging piston and said dash-pot piston, a hermetically sealed cylindrical chamber secured to and forming an extension of said cylinder, said dash-pot piston being reciprocable in and closely fitting said chamber, whereby the inward face of said dash-pot piston is subjected to the pressure of the gas confined in said chamber to limit the inward movement of said scavenging piston during each power stroke, and a magnetically-operated valve for preventing the escape around said means of the gas confined in said chamber.
17. An internal combustion engine comprising, in combination, a cylinder, a hermetically sealed cylindrical chamber secured to and forming an extension of said cylinder, a piston reciprocable in and closely fitting said chamber, a rod for said piston, a seat for said piston surrounding said rod, and an electromagnet for holding said piston to its seat, thereby to prevent the escape around said rod of the gas confined in said chamber.
18. An internal combustion engine comprising, in combination, a cylinder, a fixed head intermediate the ends of said cylinder,

a power piston in said cylinder on one side of said head, a scavenging piston located between said head and said power piston, a dash-pot piston on the other side of said head, means passing through said head and rigidly connecting said scavenging piston and said dash-pot piston, a source of compressed air, and means for conveying compressed air to the inner face of said dash-pot piston. 10

5 In testimony whereof, I have hereunto subscribed my name this 21st day of March, 1924.

HENRY H. CUTLER.
